UNITED STATES PATENT OFFICE EXAMINE

BENJAMIN F. SPRINGER, OF MCLEAN, ILLINOIS.

END-GATE FASTENER.

973,578.

Specification of Letters Patent. Patented Oct. 25, 1910.

Application filed August 10, 1909. Serial No. 512,181.

To all whom it may concern:

Be it known that I, BENJAMIN F. SPRINGER, a citizen of the United States, residing at McLean, in the county of McLean and State of Illinois, have invented certain new and useful Improvements in End-Gate Fasteners, of which the following is a specification.

My invention relates to end gate fasteners for wagons or like vehicles and has for its object to eliminate the rods now in use to brace the side boards of the same.

A further object is to provide a method of fastening by which the end gate may be held firmly in position during the process of unloading the vehicle, thus doing away with the very objectionable method of removing them every time it is necessary to empty out a part or the whole of the material in the vehicle.

An important object of the invention is to provide a novel form of retaining flange member arranged to be carried by the upper portion of the gate so that it may be held securely spaced above the bottom of the engaged wagon body to support the lower portion when in open position.

A further important object is to provide such a top retaining means that will prevent rattling thereof during movement of the carrying vehicle.

This end gate is especially adapted to grain, coal and farm wagons, and can be used on the front as well as the rear thereof.

With these and other objects in view, the present invention consists in the combination and arrangement of parts as will be hereinafter more fully described and particularly pointed out in the appended claim, it being understood that changes in the specific structure shown and described may be made within the scope of the claim without departing from the spirit of the invention.

In the drawings forming a portion of this specification, and in which like characters of reference indicate similar parts in the several views, Figure 1 is a fragmentary top plan view of a wagon supplied with my end gate, Fig. 2 is a rear view of a wagon provided with this invention, Fig. 3 is a fragmentary longitudinal section on the line 3—3 of Fig. 2, Fig. 4 is a detail perspective of the upper flange section of the end gate, Fig. 5 is a similar view of the lower section. Fig. 6 shows a section on the line 6—6 of Fig. 3 of the upper guide plate and end

gate engaged thereon, Fig. 7 is a similar view on the line 7—7 of Fig. 3 of the lower guide plate, Fig. 8 is an elevation of a modified form of guide plate for the upper gate section.

Referring more particularly to the drawings, A indicates the side boards of a wagon body of a usual form and construction, provided at their ends with metallic guide plates 6, having the guide-ways 8. These guide plates 6 are constructed of one piece of sheet metal, having two vertically extending spaced guide ribs 7 crimped therein, the plates being secured in any suitable manner against the side boards with the guide ribs projecting inwardly therefrom. These guide ribs are resilient and extend downwardly from adjacent the upper edge of the side boards approximately half their height for the reception of T-flanges 9 carried by the upper section of the gate, as will be described. It will be noted that a central portion 10 is provided in the plates between the ribs adapted to be fastened as shown to the side boards, and outwardly of the ribs there are presented flanges 11 similarly secured. It will be noted that each rib is provided with two sides or walls, the inner one being in the form of the letter V as viewed in cross section, the angle of the V-shaped portion being directed outwardly from the center of the plate 6. The inner sides of the ribs slope gradually outward from the plane of the central portion 10, as shown at 12, thence are turned inwardly for a short distance and then recurved laterally a short distance, approximately parallel to the plane of the portion 10, when they are extended toward the side board forming a buttress 12' and turned laterally again in the plane of the portion 10 to form the flanges 11.

The end gate comprises an upper section B and a lower section C hinged thereto for pendent oscillation. The upper section carries the T-flange 9, having the oppositely extending flanges 14 the outer edges of which are adapted for snug engagement in the guide-ways of the plate 6. The T-flange 9 is formed of one piece of sheet metal. It will be seen that the engagement of the flanges 14 with the ribs 7 will be resilient in its action, to a certain extent, so that the upper end gate section will be held against rattling movement. Extending upwardly from the floor of the wagon to the lower

end of the upper guide plate 6 on each side board there is a single forward guide rib 15 having opposite flanges secured to the board. The lower end gate section is provided at each end with a sheet metal plate 16 having a single flange on its inner side adapted to engage against the respective ribs 15, which are similar in formation to those numbered 7. The plate 16 is formed of a continuous piece of sheet metal which is bent to present the parallel attaching flanges engaged on opposite sides of the lower gate section C, and is crimped to form the flanges 16' projecting inwardly from the inner corner of the section C, at right angles thereto. Formed in the outer side of the portion 9' of the T-flange 9, and on the outer side 17 of the flange portion 16, there are outwardly stamped spaced ears 20, having slidably engaged therein, suitable latch pin members 21 slideable therethrough for engagement in suitable openings formed in the adjacent portion of the guide plate to hold the gate sections in operative position. Helical springs 22 are engaged around the central portion of the pins 21, being seated against one of the ears and bearing against transverse pins 23 carried in the pins 21 intermediately of the ears, the pins being thus held yieldably in engaged position.

In operation, the upper section is engaged in the guideways of the plates 6, the lower section being pendent, and the gate pressed downwardly until the lower edge of the bottom section engages snugly against the floor. By means of the pins 21 the upper section is locked against vertical movement, and the lower section is pressed inwardly against the rib member 15 and thus secured by the pins 21 carried on this section. The resiliency of the ribs 7 and 15 thus prevents the gate from rattling.

When it is desired to unload a wagon provided with this gate, if the wagon should contain dirt, coal, or like material, the lower section of the gate may simply be unloosened and swung outwardly, the removal of the material being thus permitted without detachment of the gate.

As shown in Fig. 8 the ribs 7 may be downwardly converged so as to more firmly grip the flanges 14 of the upper section of the gate, the edges of which should also be similarly convergent. When the gate is dis-

posed in operative position, the flanges 9 and 16' press outwardly against the V-shaped inner sides of the ribs 7 and 15, whereby the gate is held against lateral play.

By the construction of the ears 20 integrally with the flange members upon the gate, the manufacture of the device is considerably simplified and cheapened without impairing its efficiency.

What is claimed is:

In a device of the class described, the combination with a wagon side board, of a guideway formed from sheet material and comprising a central plane portion adapted to be disposed against the side board to form a buttress portion and being inclined outward from the side board and recurved to form a flange receiving portion, the sheet material being then again recurved laterally and extended a short distance, and being directed inwardly toward the side board, the extreme edge portions being turned in a common plane with the first mentioned central plane portion and adapted to be secured against the side board, the sides of said guideway being convergent toward the lower end; and a wagon gate comprising hinged sections, the upper having at each end a member approximately T-shaped in cross section slidable in said guideway and having oppositely extending flanges divergent toward their upper ends and resiliently held between said flange receiving portions, said flange receiving portions being adapted for lateral yielding under downward movement of the T-shaped member, the buttress being adapted to resist lateral yielding forcing the guide portions inward toward the side board, to clamp the flanges against loose play; a stop flange below the guideway extending over a portion of the height of the side board, the lower hinged section of the gate having a laterally extending flange adapted to abut the stop flange, and adapted to swing away therefrom, means for holding said upper section against vertical movement, and means for holding said lower section in engagement against said stop flange.

In testimony whereof I affix my signature, in presence of two witnesses.

BENJAMIN F. SPRINGER.
